CLAIM

The ornamental design for a light emitting diode package, as shown and described.

DESCRIPTION

FIG. 1 is a perspective view of a light emitting diode package;

FIG. 2 is a plan view of the light emitting diode package shown in FIG. 1;

FIG. 3 is a bottom view of the light emitting diode package shown in FIG. 1;

FIG. 4 is a left side view of the light emitting diode package shown in FIG. 1;

FIG. 5 is a right side view of the light emitting diode package shown in FIG. 1;

FIG. 6 is a top view of the light emitting diode package shown in FIG. 1; and,

FIG. 7 is a front view of the light emitting diode package shown in FIG. 1.

The dashed broken lines shown in the drawings illustrate environmental structure and form no part of the claimed design.

1 Claim, 7 Drawing Sheets
